POWER LAWN MOWER HOUSING

Austin Gudmundsen, Inglewood, and Ellsworth D. Wilkin,
Los Angeles, Calif.

Application March 22, 1955, Serial No. 35,158

Term of patent 3½ years

(Cl. D40—1)

Fig. 1.

Fig. 2.

Fig. 1 is a front perspective view of a power lawn mower housing showing our new design; and

Fig. 2 is a rear perspective view of the design.

The dominant features of the design reside in the portions shown in full lines.

We claim:

The ornamental design for a power lawn mower housing, as shown and described.
